UNITED STATES PATENT OFFICE.

CHARLES T. HOLST, OF CHICAGO, ILLINOIS, ASSIGNOR OF ONE-HALF TO WILLIAM J. CULLERTON, OF CHICAGO, ILLINOIS.

GUARDING MECHANISM FOR SPARK-PLUGS OF INTERNAL-COMBUSTION ENGINES.

1,353,959.

Specification of Letters Patent. Patented Sept. 28, 1920.

Application filed October 13, 1919. Serial No. 330,341.

To all whom it may concern:

Be it known that I, CHARLES T. HOLST, citizen of the United States, residing at Chicago, in the county of Cook and State 5 of Illinois, have invented a certain new and useful Improvement in Guarding Mechanism for Spark-Plugs of Internal-Combustion Engines, of which the following is a full, clear, concise, and exact description.

10 My invention relates to internal combustion engines and has for its general object the provision of improved means for guarding the spark plugs thereof. My invention has for a specific purpose the provision of means whereby a spark plug of an internal combustion engine may be rendered inoperative to prevent the running of the engine. When the engine is thus embodied it is particularly adapted for use in preventing the theft of automobiles whose power plants include internal combustion engines and their spark plugs.

In practising my invention I employ a container for the spark plug mounted in connection with the engine, this container being formed with a container closing portion whereby the spark plug may be either inclosed or made accessible. Said container closing portion is provided with locking means for holding it in closed position to guard the spark plug from tampering. A spark plug short circuiting contact is carried by the container closing portion to be in short circuiting engagement with the current conductor upon the outer end of the spark plug when said container is closed. In the preferred embodiment of the invention the aforesaid container closing portion constitutes a body portion of the container and houses a plurality of contact springs which are carried thereby, these springs being of differing lengths to be engageable, when the container is closed, with the current conductor upon the outer end of one of a plurality of spark plugs of differing lengths, employed on the engine.

I will explain my invention more fully by reference to the accompanying drawing in which Figure 1 is a view, partially in section and partially in elevation, illustrating the equipment of my invention as applied to an internal combustion engine, a small portion of the engine being only shown for lack of space; Fig. 2 is a sectional view on line 2—2 of Fig. 1; Fig. 3

is a sectional view on line 3—3 of Fig. 1; Fig. 4 is a sectional view on line 4—4 of Fig. 1; and Fig. 5 is a plan view of a container for the spark plug as such container is preferably formed.

Like parts are indicated by similar characters of reference throughout the different figures.

I have illustrated a portion 1 of an internal combustion engine having a plurality of cylinders each equipped with a spark plug 2 that is carried by the engine and whose sparking electrodes 3 and 4 are within the explosive gas receiving portion of the engine. Each spark plug has a container for inclosing it, this container preferably comprising a lesser portion 5 mounted upon or otherwise in connection with the engine and a body portion 6. All of the body portions 6 of the containers are 60 fixed upon a common shaft 7 whereby they may be simultaneously placed in closed positions to inclose the spark plugs or in open positions to render such spark plugs accessible. The containers are made long enough 65 so that they may be applied to engines having contact plugs of differing lengths. A plurality of contact springs 8 are mounted within each swinging container portion 6 and are housed therein. These springs 70 are of different lengths so that one or another of them will be engageable with the current conductor 9 upon the outer end of the spark plug that is within such container. Each sparking electrode 10 is included in circuit with a suitable source of current by means of the conducting portion 9 upon the outer end of the spark plug insulated wire 11 extending to such source of current. The electrode 12 complementary 75 to the electrode 10 is grounded upon the frame of the engine as are also the swinging container portion 6 and the contacting springs 8 carried thereby.

Whenever the engine is to be rendered inoperative the container is closed so that the spark plug conductor 9 and the sparking electrode 10 are grounded and short circuited.

Some suitable locking means is employed 80 for holding the container closing portion 6 in closed position. In the preferred embodiment of the invention the locking structure is mounted on the front side of the dash board 13, in the event that the device of my 85

invention is applied to an automobile. Locking mechanism has a container whose body portion 14 is mounted upon the dash board and whose lid portion 15 is pivoted 5 to the body portion at 16 and is held fast with respect thereto by means of screws 17. A rack frame 18 is mounted to slide up and down in the container 14, 15, this rack frame carrying a knob 19 upon the exterior of the 10 container 14, 15 whereby this rack frame may be moved up and down. The stem of the knob passes through the upright slot 20 in the container portion 15. The rack frame carries a rack 21 that engages a seg- 15 mental pinion 22 fixed upon the shaft 7. When the knob 19 is down the body portions 6 of the containers 5, 6 are open as indicated by dotted lines in Fig. 3 to remove the short circuiting springs 8 that 20 are engageable with the spark plug conductors 9 to remove the short circuits from the spark plugs to permit the engine to run. When said knob is uppermost the container closing body portion 6 25 is in closed position as shown in full lines in Fig. 3. One side of the rack frame 18 has openings 23, 24 extending therethrough. When the rack frame is in its uppermost position, at which time the spark plug con- 30 tainer is closed, the opening 23 is in register with the recess 25 formed in the body portion 14 and the container 14—14. When the swinging body portion 6 of the plug container is fully open the opening 24 in the 35 rack frame is in register with the recess 25. The cover portion 15 of the container 14—15 carries a lock 26. The bolt 27 of this lock is in alinement with the recess 25 and may be passed into this recess through the open- 40 ing 23 when the spark plug containers are to be closed and the spark plugs therein are to be short circuited to prevent the engine from operating, or through the opening 24 when the spark plug containers are to be 45 opened and the short circuits upon the spark plugs are to be removed in order to permit the engine to operate. The upper end of the rack frame 18 is forwardly deflected to provide a curved space for the screw 28 that 50 takes part in fastening the container portion 14 to the dash board. When the bolt of the lock is in locking position the container portion 15 cannot be swung upon its hinge 16 even though the screw 17 be removed. The 55 lower portion 18' of the rack bar is thickened substantially to span the space between the container portions 14—15 thereby to give the rack bar proper direction of movement.

60 While I have herein shown and particularly described the preferred embodiment of my invention I do not wish to be limited to the precise details of construction shown as changes may readily be made without de- 65 parting from the spirit of my invention, but

having thus described my invention I claim as new and desire to secure by Letters Patent the following:—

1. An internal combustion engine having a spark plug carried by the engine and having sparking electrodes within the explosive gas receiving portion of the engine; of a container for the spark plug mounted in connection with the engine and formed with a swinging body portion and a comple- 75 mental closure portion whereby the spark plug may be either inclosed or made accessible; a lock for holding the swinging body portion in closed position; and a plurality of contacts carried by the swinging body portion and of differing lengths to be engageable, when the container is closed, with the current conductor upon the outer end of one of a plurality of spark plugs of differing lengths, employed as the aforesaid spark 80 plug, said contacts being in spark plug short circuiting connection.

2. An internal combustion engine having a spark plug carried by the engine and having sparking electrodes within the explosive 90 gas receiving portion of the engine; of a container for the spark plug mounted in connection with the engine and formed with a swinging container closing portion whereby the spark plug may be either inclosed or 95 made accessible; a lock for holding the swinging container closing portion in closed position; and a plurality of contacts carried by the swinging container closing portion and of differing lengths to be engageable, 100 when the container is closed, with the current conductor upon the outer end of one of a plurality of spark plugs, said contacts being in spark plug short circuiting connection.

3. An internal combustion engine hav- 105 ing a spark plug carried by the engine and having sparking electrodes within the explosive gas receiving portion of the engine; of a container for the spark plug mounted in connection with the engine and formed with a swinging body portion and a comple- 110 mental closure portion whereby the spark plug may be either inclosed or made acces- 115 sible; a lock for holding the swinging body portion in closed position; and a spark plug short circuiting contact carried by the swinging body portion to be in short circuiting engagement with the current conductor upon the outer end of the spark plug when 120 said container is closed.

4. An internal combustion engine having a spark plug carried by the engine and having sparking electrodes within the explosive gas receiving portion of the engine; of a container for the spark plug mounted in connection with the engine and formed with a swinging container closing portion whereby the spark plug may be either inclosed or 125 made accessible; a lock for holding the 130

swinging container closing portion in closed position; and a spark plug short circuiting contact carried by the swinging container closing portion to be in short circuiting engagement with the current conductor upon the outer end of the spark plug when said container is closed.

5. An internal combustion engine having a spark plug carried by the engine and having 10 sparking electrodes within the explosive gas receiving portion of the engine; of a container for the spark plug mounted in connection with the engine and formed with a container closing portion whereby the 15 spark plug may be either inclosed or made accessible; a lock for holding the container closing portion in closed position; and a plurality of contacts carried by the container closing portion and of differing 20 lengths to be engageable, when the container is closed, with the current conductor upon the outer end of one of a plurality of spark plugs, said contacts being in spark plug short circuiting connection.

25. 6. An internal combustion engine having a spark plug carried by the engine and having 30 sparking electrodes within the explosive gas receiving portion of the engine; of a container for the spark plug mounted in connection with the engine and formed with a container closing portion whereby the 35 spark plug may be either inclosed or made accessible; a lock for holding the container closing portion in closed position; and a 40 spark plug short circuiting contact carried by the container closing portion to be in short circuiting engagement with the current conductor upon the outer end of the spark plug when said container is closed.

40. 7. An internal combustion engine having

a spark plug carried by the engine and having 45 sparking electrodes within the explosive gas receiving portion of the engine; of a container for the spark plug mounted in connection with the engine and formed with a swinging body portion and a complementary closure portion whereby the spark plug may be either inclosed or made accessible; and a lock for holding the swinging body portion in closed position. 50

8. An internal combustion engine having a spark plug carried by the engine and having 55 sparking electrodes within the explosive gas receiving portion of the engine; of a container for the spark plug mounted in connection with the engine and formed with a container closing portion whereby the 60 spark plug may be either inclosed or made accessible; and a lock for holding the container closing portion in closed position. 60

9. An internal combustion engine having a spark plug carried by the engine and having 65 sparking electrodes within the explosive gas receiving portion of the engine; of a container for the spark plug mounted in 70 connection with the engine and formed with a container closing portion whereby the spark plug may be either inclosed or made accessible; a lock for holding the container closing portion in closed position; and a 75 spark plug short circuiting contact operated by the container closing portion to be in short circuiting engagement with the current conductor upon the outer end of the spark plug when said container is closed.

In witness whereof I hereunto subscribe my name this 9th day of October, A. D. 1919.

CHARLES T. HOLST.
